UNITED STATES PATENT OFFICE.

CYRUS W. FLINT, OF ST. LOUIS, MISSOURI, ASSIGNOR TO JOSEPH ROSE, OF MEMPHIS, TENNESSEE.

SPRING-BED.

SPECIFICATION forming part of Letters Patent No. 511,691, dated December 26, 1893.

Application filed April 13, 1891. Serial No. 388,935. (No model.)

To all whom it may concern:

Be it known that I, CYRUS W. FLINT, a citizen of the United States, and a resident of St. Louis, in the State of Missouri, have invented 5 certain new and useful Improvements in Spring-Beds; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to spring beds the 15 object being to construct such an article of hour glass springs in such a manner, as far as practical, as to obtain a perfect integrality of the entire structure, the details of all of which will be hereinafter fully described and 20 the elements and combinations for which special novelty is claimed will be hereinafter specified.

In the accompanying drawings, Figure 1 is 25 a plan of the device in which figure, for convenience of illustration, the springs are proportionally too large and a fewer number used than the usual custom in manufacture. Fig. 2 is a plan view of a portion of one of the springs more clearly showing the manner 30 of bending the free end of the coil around the top coil and extending it. Fig. 3 is a side elevation partly in section showing the arrangement and connection of the springs. Fig. 4 is a portion of a spring and a transverse rod showing the upwardly bent portion 35 of the spring and the transverse rod shown near "3" in Fig. 3.

In the drawings like reference marks are 40 employed in the designation of corresponding elements of construction in all the views.

1 is the frame of wire or other suitable material. A joint 2 is employed to connect the free ends of the wire when said frame is of such. Cross bars 3 extend transversely or 45 longitudinally of the frame and for a purpose presently to be mentioned have kinks or bends 4 therein at intervals. These bars 3 are secured to the frame 1 at the desired points and extend in the construction of the 50 device shown, in a direction parallel to the

bars of the frame 1, other than the ones to which they are secured.

The springs 5 are in the usual form, and have their ends looped around or otherwise securely fastened to the uppermost coil, the 55 loop 6 being preferable and the said end is extended for a sufficient distance beyond said loop in a horizontal plane, (otherwise the plane of the top of the spring,) and a hooked or turned back portion 7 formed on the end 60 thereof, the free end of said hook being turned downwardly to prevent a disruption of the hereinafter specified engagement of said hook 7 with the bar 3 and the spring 5. At its point of contact with one of the bars 3 65 the top coil of the spring 5 is bent downwardly at approximately an angle of forty-five degrees. Said bend is numbered 8 in the drawings.

In connecting the springs the hook 7, bar 70 3 and loop 8 are engaged in the manner shown in Figs. 3 and 4, the bar 3 being placed at the bending point of the spring resting under the uppermost coil of said spring as shown, the kinks 4 contacting with the spring at the 75 bending points and preventing the said spring from slipping on the bar, and the loop 7 is engaged by hooking it over the wire 3 centrally between the two kinks and passing the end through between the wires 3 and 8 80 and giving it a movement downwardly so as to bring the downwardly bent end 9 into the position shown in Fig. 3.

As shown in Fig. 1 the outside hooks 7 are hooked over the frame 1 and down the center 85 of the bed the springs are consequently so set that two loops 8 are contiguous. To connect the two middle rows together, wires 10 are used which have loops 7 and downward extensions 9 thereon at each end functionally 90 the same as the loops and extensions hereinbefore described as belonging to the extensions 11 of the springs.

Having thus described my invention, what I claim as new, and desire to secure by Letters 95 Patent of the United States, is—

In a spring bed, the combination of a frame, the springs each having its end coils provided with the bends 8, extending toward the longitudinal center of the bed and away from 100

the axis of the spring, the tie rods extending along the inner sides of the end coils of the springs and having the kinks fitting the coils at the ends of the bends, and the lateral arms 5 connecting the end coils of the springs, each arm passing over the bend of the adjacent end coil and over the tie rod, and having the hook engaging the tie rod, the free end of which passes between the tie rod and center

of said bend 8, and is bent down at the outer side of said bend, substantially as described.

In testimony whereof I hereunto affix my signature in presence of two witnesses.

CYRUS W. FLINT.
